Patented Oct. 13, 1925.

UNITED STATES PATENT OFFICE.

CORWILL JACKSON, OF CHICAGO, ILLINOIS.

TAMPING OR BALLASTING MACHINE.

Application filed July 25, 1924. Serial No. 728,099.

To all whom it may concern:

Be it known that I, CORWILL JACKSON, a citizen of the United States, residing at Chicago, county of Cook, State of Illinois, have invented certain new and useful Improvements in Tamping or Ballasting Machines, of which the following is a specification.

This invention relates to improvements in tamping or ballasting machines.

The main object of this invention is to provide an improved tamping or ballasting machine which is highly efficient and at the same time easily manipulated.

Objects pertaining to details and economies of my invention will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a fragmentary side elevation of a structure embodying the features of my invention, the same being shown in operative relation to a railway track.

Fig. I^a is a detail elevation showing the tamper blades of Fig. I in another actuated position.

Fig. II is a detail view partially in vertical section on a line corresponding to line 2-2 of Figs. I and III.

Fig. III is a horizontal section on a line corresponding to line 3-3 of Figs. I, II and IV.

Fig. IV is a fragmentary side view of a modified form of my invention, the modification being in the form of the tamper blades.

In the drawing the sectional views are taken looking in the direction of the little arrows at the ends of the section lines and similar numerals of reference indicate similar parts in all of the views.

Referring to the drawing, 1 represents a supporting frame, in practice a truck adapt-

ed to travel upon a railway track. The head member 2 is carried by an arm 3 supported to be raised and lowered by means of the cable 4, the means for operating the cable not being illustrated.

Upon the head member I mount vertical ways 5 carrying an impact means, as illustrated, consisting of a cylinder 6 with piston 7 therein having an impact head 8. The control valves and connections for the cylinder are not illustrated. The cylinder is adjustably supported in the ways by means of the screw 8.

Supported in ways below the impact means is a tamper crosshead 9 carrying the tamper arm 10 which is pivoted to the crosshead at 11 so that it hangs from the crosshead. On the lower end of this arm I mount a pair of tamper blades 12, the blades being carried by the pivot 13 and having laterally projecting arms 14 which are adapted to engage a pair of adjacent ties, as illustrated in Fig. I^a, thereby spreading the blades, the crosshead at the same time being subject to the blows of the impact means.

Buffer springs 15 are provided for the crosshead, these springs being carried by the rods 16 disposed through the crosshead, the rods being adjustable with the cylinder so that the same relative relation is maintained for the impact means and the crosshead as the parts are fed downwardly by means of the screw 8.

In the modification shown in Fig. IV the tamper blades 17 are pivoted directly to the crosshead, these blades being arranged in coacting pairs back to back, the lower ends of the blades being diverged as shown so that they tend to separate when they come in contact with the ballasting material.

With the parts thus arranged the tamper blades are fed downwardly into the material to be compacted, at the same time being subjected to a series of impacts with the result that the material is effectively tamped under and around the ties.

I have not attempted to illustrate certain other embodiments or modifications which I contemplate as I believe the disclosure

made will enable those skilled in the art to embody or adapt my improvements as may be desired.

Having thus described my invention 5 what I claim as new and desire to secure by Letters Patent is:

1. In a structure of the class described, the combination with a supporting head provided with vertical ways, of an impact 10 means comprising an impact member mounted for vertical adjustment in said ways, a tamper crosshead reciprocating in said ways below said impact means, buffer springs for said tamper crosshead carried by said impact means, means for raising and lowering said impact means, a tamper arm pivotally mounted on said tamper crosshead, tamper blades pivotally mounted on said arm in coacting pairs to pass between a pair of adjacent ties and provided with laterally projecting arms adapted to engage the tie members whereby the blades are separated, and means for raising and lowering said supporting head. 15
2. In a structure of the class described, the combination with a supporting head provided with vertical ways, of an impact means comprising an impact member mounted for vertical adjustment in said ways, a tamper crosshead reciprocating in said ways below said impact means, buffer springs for said tamper crosshead carried by said impact means, means for raising and lowering said impact means, a tamper arm pivotally mounted on said tamper crosshead, tamper blades pivotally mounted on said arm in coacting pairs, and means for raising and lowering said supporting head. 20
3. In a structure of the class described, the combination with a supporting head provided with vertical ways, of an impact means comprising an impact member mounted for vertical adjustment in said ways, a tamper crosshead reciprocating in said ways below said impact means, buffer springs for said tamper crosshead carried by said impact means, means for raising and lowering said impact means, and tamper blades pivotally mounted on said crosshead in coacting 25 pairs to pass between a pair of adjacent ties and provided with laterally projecting arms adapted to engage the members whereby the blades are separated. 30
4. In a structure of the class described, the combination with a supporting head provided with vertical ways, of an impact means comprising an impact member mounted for vertical adjustment in said ways, a tamper crosshead reciprocating in said ways below said impact means, buffer springs for said tamper crosshead carried by said impact means, means for raising and lowering said impact means, and tamper blades pivotally mounted on said crosshead in coacting 35 pairs. 40
5. In a structure of the class described, the combination with a supporting head provided with vertical ways, of an impact means comprising an impact member mounted for vertical adjustment in said ways, a tamper crosshead reciprocating in said ways below said impact means, buffer springs for said tamper crosshead carried by said impact means, means for raising and lowering said impact means, and a tamper mounted 45 on said crosshead. 50
6. In a structure of the class described, the combination of an impact means, a tamper head operatively associated therewith, a tamper arm pivotally mounted on said tamper head, and tamper blades pivotally mounted on said arm in coacting pairs and provided with laterally projecting arms adapted to engage adjacent ties, for the purpose specified. 55
7. In a structure of the class described, the combination of an impact means, a tamper head operatively associated therewith, a tamper arm pivotally mounted on said tamper head, and tamper blades pivotally mounted on said arm in coacting pairs. 60
8. In a structure of the class described, the combination of an impact means, a tamper head operatively associated therewith, and tamping blades pivotally mounted on said impact member in coacting pairs and provided with laterally projecting arms adapted to engage a pair of adjacent ties after the blades are in engagement with the material to be tamped. 65
9. In a structure of the class described, the combination with an impact means, of a tamping member operatively associated therewith, and tamper blades pivotally mounted on said tamping member in coacting oppositely disposed pairs. 70
10. In a structure of the class described, the combination with an impact means, of a tamper member operatively associated with said impact means and having tamping blades pivotally mounted thereon in opposed coacting pairs, said blades being provided with arms adapted to engage with adjacent ties whereby the blades are separated while engaged with the material to be tamped. 75
11. A structure of the class described, comprising a tamper member having tamping blades pivotally mounted thereon in opposed coacting pairs, said blades being provided with arms adapted to engage with adjacent ties whereby the blades are separated while engaged with the material to be tamped. 80
12. In a structure of the class described, the combination with an impact means, of a tamper member operatively associated with said impact means, and a tamping blade pivotally mounted on said tamper member and provided with a laterally pro- 85

jecting arm adapted to engage a tie for the purpose specified.

13. In a structure of the class described, the combination with an impact means, of 5 a tamper head operatively associated with said impact means, and a pair of tamping blades pivotally mounted on said tamping head in coaxing pairs back to back to swing from an approximately vertical to 10 ward a horizontal position while in contact with the material worked upon.

14. In a structure of the class described, the combination with an impact means, of a tamper member operatively associated with said impact means, and a tamping 15 blade pivotally mounted on said tamper member to swing from an approximately vertical toward a horizontal position while in contact with the material worked upon.

In witness whereof I have hereunto set 20 my hand.

CORWILL JACKSON.
